REVOLVING DISPLAY CASE

Charles F. Shisler, Wooster, Ohio

Application March 28, 1935, Serial No. 13,089
Renewed March 3, 1937

1 Claim. (Cl. 312—98.5)

This invention appertains to new and useful improvements in display cases and more particularly to a case for displaying merchandise for immediate sale.

5 An important object of the invention is to provide a rotary case in which meat and other perishable goods can be placed and attractively displayed.

10 Another important object of the invention is to provide a revolving display case divided into a plurality of radial areas separably illuminated and having switch means associated therewith whereby each area will become illuminated as it reaches the front side of the case.

15 These and various other important objects and advantages of the invention will become apparent to the reader of the following specification.

In the drawings:

Figure 1 represents a front elevational view of the case.

20 Figure 2 represents a vertical sectional view through the case.

Figure 3 represents a horizontal sectional view taken substantially on line 3—3 of Figure 2.

25 Figure 4 represents a fragmentary vertical sectional view principally through the drive means for the case.

Figure 5 represents a perspective view of one of the pivotal windows.

30 Figure 6 represents a fragmentary perspective view of one of the window frames.

Figure 7 represents a horizontal sectional view taken substantially on line 7—7 of Figure 1.

35 Figure 8 represents a diagrammatic view of the electrical connection between the switch means, lamps and source of energy.

Figure 9 is a perspective view of one of the spacers.

40 Referring to the drawings wherein like numerals designate like parts, it can be seen that numeral 5 represents a housing for the drive mechanism, this housing being provided with a well 6 in the top thereof for containing the bearing 7 through which the vertical shaft 8 extends, this shaft 8 extending vertically and axially through the case proper generally referred to by numeral 9, and also depending into the housing 5.

45 The case 9 includes a top 10 and a bottom 11. It will be observed that the case is preferably of polygonal shape in horizontal section, which shape defines multiple sides, each of which contains a column of pivotal windows as clearly shown in Figures 1 and 2.

50 The top and bottom walls 10—11 are connected

5 by vertical posts 12, each pair of adjacent posts defining the width of one side of the case, while the top and bottom walls 10—11 define the height of the particular side. Within each side of the case and suitably set in a rabbet is the window frame 13 which is of rectangular shape and provided with cross members 14 at regular intervals as clearly shown in Figure 1. These cross members 14 in conjunction with the frame 13 define window spaces and each of the cross members 14 is on a line with a shelf 15. There are any number of vertically spaced shelves in the case, suitably secured to and supported by the posts 12.

10 At this point it will be observed, that the shaft 8 extends upwardly through the shelves 15 and through the top 10 of the case where it is threaded and equipped with a nut 16. The shaft 8 is keyed to the base plate 11a of the case, the latter in turn being secured to the case. Fabricated spacers 17 are of longitudinally tapered 15 tubular construction, with the small ends thereof fitting into the large ends thereof in the manner shown in Figure 2 to provide a continuous conduit for electrical wires to the lamps 51, the spacers being fabricated to afford openings as 20 shown in Figure 9 through which the wires can be trained.

25 Within each of the window spacers aforementioned is a pivotal sash 18 containing a transparent pane 19, each sash 18 being provided at its lower corner with pintles or trunnions 20 which engage into corresponding openings 21 in the frame 13. (See Figure 6.)

30 Between the uppermost shelf 15 and the next underlying shelf 15 is a tubular container 22 surrounding the shaft 8 and adjacent the spacer 17. This container is intended to receive ice or some other agent for reducing the temperature of the air within the case. The container 22 is provided with a drain pipe 23 and underlies an 35 opening 24 in the overlying shelf 15 which is normally provided with a cover 25.

35 As is clearly shown in Figures 2 and 3 the upper compartment of the case is provided with a removable display tray 26 which assumes the inclined position shown in Figure 2. This tray as clearly shown in Figure 3 is of segmental shape of a sector suitable for displaying merchandise to one side of the case.

40 The drive means for the case in addition to the aforementioned shaft 8 is contained within the housing 5 and involves an electric motor 27, on the armature shaft 28 on which is located the worm 29. The worm 29 meshes with the circumferentially grooved gear 30 on the shaft 31, which 45

50

shaft 31 carries a worm 32 which in turn meshes with the grooved gear 33 which is rotatably mounted on the lower portion of the shaft 8 and is supported by the bearing plate 34 which is 5 secured to the shaft 8.

The gear 33 is provided with the crown 35 having clutch teeth which are meshable with the clutch teeth of the slide collar 36, this slide collar being operative on the shaft 8 and being splined 10 thereto as at 37. The collar 36 is circumferentially grooved as at 38 and into this engages the pintles 39 on the yoke 40. The yoke 40 is provided with an arm 41 which extends horizontally through an opening 42 in the housing 5 and is 15 provided with the downturned outer end portion 43 terminating in a foot plate or pedal 44. A pivotal catch 45 is mounted adjacent the pedal 44 so that when desired the pedal can be retained depressed to maintain the clutch disengaged. 20 The housing 5 is provided with ears 46 to which the arm 41 is pivotally connected as at 47.

It will be observed in Figures 1, 4 and 7, that the housing 5 carries an arcuate shaped dielectric body 48 carrying a pair of contact strips 49 25 against which the spring brushes 50—50 on the bottom side of the bottom 11 are capable of wiping. This contact block and the strips 49 are located at the front side of the cabinet so that as the contacts 50 engage the strips 49 the 30 bulbs in the compartments above the particular side will become energized. More particularly

when the contacts 50 ride off of the conductors 49 and the compartments on that side become darkened, the contacts of the succeeding side of the case commence to engage with the strip 49 and result in the illumination of this last 5 mentioned side of the case, so that there is only one side of the case illuminated at a time as it passes a point of best observation by passersby.

While the foregoing specification sets forth the invention in specific terms, it is to be understood 10 that numerous changes in the shape, size and materials may be resorted to without departing from the spirit or scope of the invention as claimed hereinafter.

Having described the invention, what is 15 claimed is:

A case of the character described comprising a vertically disposed cabinet, a drive mechanism housing, a vertical shaft supported by the housing and supporting the said cabinet, means in 20 the housing for rotating the said shaft, said cabinet being of polygonal shape in horizontal sections, said cabinet being provided with a plurality of horizontal shelves vertically spaced and tubular spacers on the shaft for spacing the shelves 25 apart, said spacers being of tapered construction, with the lower reduced ends thereof fitting into the enlarged ends of underlying spacers, and each shelf resting upon the enlarged upper end of a 30 spacer.

CHARLES F. SHISLER.
